UNITED STATES PATENT OFFICE.

JAMES P. KELLY, OF ALEXANDRIA, INDIANA.

DESIGN FOR AN AX OR HATCHET.

SPECIFICATION forming part of Design No. 29,680, dated November 15, 1898.

Application filed July 25, 1898. Serial No. 686,847. Term of patent 14 years.

To all whom it may concern:

Be it known that I, JAMES P. KELLY, a citizen of the United States, residing at Alexandria, in the county of Madison and State of Indiana, have invented and produced a new and original Design for Axes or Hatchets, of which the following is a specification.

In the accompanying drawings, which form a part hereof, Figure 1 is a side elevation of an ax or hatchet, showing my new design; and Fig. 2 is a central sectional view of the same on the dotted line 2 2 in Fig. 1.

As shown in said drawings, the leading or material feature of my design consists in an ax or hatchet having a depression in each face thereof, said depression commencing a short distance above the bit or cutting edge thereof and extending from thence in a plane surface to the eye. The lower edges of these depressions are bounded by curved lines of

substantially or approximately the same curvature as the cutting edge of the ax. The result is that a considerable part of the middle portion of each side of the blade has the appearance of a sunken background, while the bit of the ax or hatchet stands out in relief.

Having thus fully described my said invention, what I claim as new, and desire to secure by Letters Patent, is—

The design for an ax or hatchet substantially as shown and described.

In witness whereof I have hereunto set my hand and seal, at Indianapolis, Indiana, this 21st day of July, A. D. 1898.

JAMES P. KELLY. [L. S.]
